MODULATED CARRIER WAVE
TRANSMITTER

Ernest Green, Writtle, Chelmsford, England, assignor to Radio Corporation of America, a corporation of Delaware

Application December 8, 1936, Serial No. 114,735
In Great Britain January 8, 1936

6 Claims. (Cl. 179—171)

This invention relates to radio and other modulated carrier wave transmitters and more particularly to transmitters of the so-called series modulation kind, i. e., of the kind wherein modulation is effected by a tube or bank of tubes whose internal impedance or impedances forms part of a series circuit which also includes the internal impedance or impedances of a tube or bank of tubes (and their associated circuits) operating at the carrier frequency to be modulated.

According to the main feature of this invention the control grid voltage applied to the grid or grids of the modulator tube or tubes of a transmitter of the kind referred to includes a unidirectional varying component which is derived by rectifying the modulated energy.

Though not limited to its application thereto, the main feature of this invention is especially suited for application to a so-called "floating carrier" system as described in the specification of British Patent #427,026 accepted April 15, 1935.

According to a second feature of this invention the control grid voltage applied to the grid or grids of the modulator tube or tubes of a transmitter of the kind referred to includes a unidirectional substantially fixed bias component derived from the main high tension supply which is utilized to supply potential across the series modulation circuit.

30 Preferably both features of this invention are employed together.

For the sake of convenience in the description which follows the carrier frequency tube or bank of tubes whose internal impedance or impedances together with associated circuits are, in a series modulation system, connected in series with the anode-cathode space or spaces of the modulating tube or bank of tubes across the main high tension supply, will be referred to briefly as the "load resistance". In practice, of course, this load resistance will generally be constituted by circuits including the anode-cathode space or spaces of a carrier frequency amplified tube or bank of tubes whose grid circuit input consists of the carrier frequency to be modulated.

The invention is illustrated in the accompanying drawings which, in Figures 1 to 5 inclusive, show diagrammatically several embodiments of my modulation circuit, while Figure 1a shows a detail of the circuits of the other figures.

Referring first to Figure 1 which shows one way of carrying out the first feature of this invention, the load resistance which in this case is the modulated stage, represented at R is connected at one end to the positive terminal +HT of the

main high tension supply and at the other to the anode of a modulator tube M whose cathode is connected to earth and also to the negative terminal of the said main high tension supply. The grid circuit of the modulating tube includes three resistances R₁, R₂ and R₃ in series. Modulating potentials from any suitable source, represented at G, are applied across the resistance R₁ nearest the grid. A suitable fixed bias potential V₂ from a source 10 is applied across the second resistance R₂; and the third resistance R₃ is connected through a choke L which may be replaced by a resistance or other smoother element, across the output leads from a full wave rectifier network. The resistances R₂, R₃ are shunted by by-pass condensers C₂, C₃ respectively. The full wave rectifier network includes a transformer T having a center-tapped secondary in series with two rectifiers S which may be of the copper oxide type, the center tap of the secondary winding of transformer T and the junction point of the two rectifiers S constituting the output leads from the network. The primary winding of the transformer T is connected in series with a suitable condenser C between the anode and cathode of the modulator tube M. With this arrangement a component of bias V₁ derived via the rectifier network by rectifying modulated carrier energy will be applied across resistance R₃.

In a modification illustrated in Figure 2 the load resistance R in series with the modulator tube M is on the negative side thereof, that is, is between the cathode and earth, instead of on the positive side thereof, that is, between its anode and the positive high tension terminal, as in Figure 1, and the primary winding of the transformer T, with its series condenser C is connected across the load resistance R instead of across the modulator tube M. As before the fixed bias potential V₂ may be obtained from a separate source 10.

It is preferred, however, as shown in the further embodiment of Figure 3 to obtain the bias V₂ from the main high tension supply by connecting a suitable high resistance R₅ between the negative terminal of the high tension supply source (earth) and the junction point of the resistances R₁ and R₂. If desired, and again as shown in Figure 3, a variable resistance R₄ may also be connected in series with the primary winding of the transformer T, while also, if desired, the choke L may be replaced by a resistance R₆ (Figure 3). In Figure 3 essential elements of the modulated stage represented by R in the prior figures have been shown. This modulated stage 55

may comprise an electron discharge device 20 having its anode 22 connected to the cathode of M and its cathode 25 connected by way of a radio frequency choke coil to ground as shown so that the primary winding of transformer T is in parallel with the impedance between the electrodes 22 and 25 of tube 20. A high frequency circuit is connected as shown by blocking condensers BC between the anode and cathode of tube 20 in conventional fashion. A high frequency source is connected as shown in Figure 1a between the control grid 24 and cathode 25 in the conventional manner.

The modulated stage shown in Figure 3 may be used also in Figures 1, 2, 4, and 5 to replace R or as pointed out hereinafter a modulated stage as shown in Figure 1a may be used in all of the figures.

In a further embodiment shown in Figure 4 there are two modulator tubes M₁, M₂ having their anodes connected together and also their cathodes connected together. The anodes of the tubes M₁, M₂ are connected to the positive high tension terminal HT+ and the cathodes are connected to earth and to the negative high tension terminal through the load resistance R. The modulator tube grids are connected as shown each to an adjustable tapping point upon a different one of two resistances R_{1'}, R_{1''}. These resistances are connected at their upper ends each through a coupling condenser to one terminal of the modulating potential source at G the lower ends of the said resistances being adjustably tapped upon a resistance R₂ one end of which is connected to earth through a high resistance R₆ and the other end of which is connected through a further resistance R₃ to the cathode point. Suitable by-passing and filtering condensers C_{1'}, C₂ and C₃ are provided as shown. The junction point of resistances R₂, R₃ is connected through a choke or other smoothing element, such as a resistance R₄, to one output lead of a full wave rectifier network T, S, the other output lead of which is connected to the modulator tube cathode point. The full wave rectifier network is as in the previous embodiments and the primary of the transformer T therein is connected in series with a condenser C across the load resistance R. The remaining terminal of the modulating potential source at G is connected to the tapping point at which resistance R_{1''} is connected to resistance R₂.

In Figures 1 and 2, V₂ is provided from an external insulated source, the negative terminal 55 being towards the tube grid. In the absence of modulation this backs off M to a low feed value. When modulation is applied, the rectifiers S provide a voltage V₁ across R₃ in opposition to V₂. This reduces the resultant negative bias on M and allows the feed to increase.

In Figures 3 and 4 the fixed bias of M is obtained from the current flowing through R₃, R₄, and then R₅.

This variable bias due to modulation is provided 65 by S across R₃ and must be sufficient to overcome the increase of steady bias due to the increase of feed through M, R₃ and R₂.

Figure 5 shows a preferred embodiment of the 70 second feature of this invention. Here the grid circuit of a modulator tube M, which is in series with the load resistance R across the high tension supply and is on the positive side, contains in series with a resistance R₁ across which modulating potentials from G are applied, a further resistance R₂ which is shunted by a condenser C₂

of sufficient magnitude to by-pass all modulating frequencies. The junction point of resistances R₁, R₂ is connected through another resistance R₅ to the earthed or negative supply terminal end of the load resistance R. The resistances R₂ and R₅ are of large value and take a very small fraction of the main current, being chosen of such value as to give the desired value of negative bias at the grid of the modulator tube.

The impedance R of each of Figures 1, 2, 4, and 5 includes the impedance of a tube 20 having electrodes connected as shown in Figure 1a. In other words, the circuits and tube of Figure 1a may replace the rectangle R in each of the other figures of the drawings. This is accomplished by 10 breaking the leads to R at points 26 and 28 of the various figures and connecting points 26 and 28 of Figure 1a to said points respectively. Moreover, the modulated stage of Figure 3 may in like manner replace R of the remaining figures and the modulated stage of Figure 1a may replace the modulated stage of Figure 3.

I claim:

1. In a modulation system of the type wherein a discharge tube stage has electrodes connected in an alternating current circuit in which wave energy to be modulated is caused to flow and having output electrodes connected in a series modulation circuit with a modulating tube having electrodes on which modulating potentials are impressed, both being connected with a source of direct current potential, to accomplish modulation of said wave energy by said modulating potentials, means for impressing a direct current biasing potential on a controlling electrode of 25 said modulating tube, an impedance for impressing an additional controlling potential on a controlling electrode of said modulating tube which varies in accordance with the modulations on said wave energy, and rectifying means coupling electrodes of said discharge tube to said impedance to impress thereon additional controlling potentials to control the bias of said modulating tube in accordance with the modulations on said wave energy.

2. In a modulation system, a discharge tube stage having electrodes connected in an alternating current circuit in which wave energy to be modulated is caused to flow and having output electrodes, a modulating tube having electrodes on which modulating potentials are impressed and having output electrodes, a source of direct current potential, means connecting the output electrodes of said discharge tube and said modulating tube in series across said source of direct current potential, resistive means connected with said direct current source and a controlling electrode of said modulating tube for impressing a direct current biasing potential on said electrode of said modulating tube, a second resistive means connected with said last named resistive means for impressing a variable controlling bias on said last named electrode, a rectifier having input electrodes coupled with electrodes of said discharge tube stage to derive therefrom modulated wave energy and rectifying the same to derive a component characteristic of the modulations on said modulated wave energy, and a circuit connecting the output electrodes of said rectifier to said second resistive means to impress thereon additional controlling potentials to control the bias of said modulating tube in accordance with the modulations on said wave energy.

3. In a modulation system, a carrier frequency tube having electrodes on which wave energy to 75

be modulated may be set up, a modulator tube having input electrodes on which modulating potentials may be impressed and having output electrodes, a source of direct current potential, 5 means connecting the impedances between electrodes of said first tube and between the output electrodes of said modulating tube in series and to said source of direct current potential, resistive means for impressing a direct current biasing potential, on a controlling electrode of said modulator tube, a second resistive means connected with said last named resistive means, a rectifier having input electrodes coupled with electrode of said carrier frequency tube to derive therefrom 10 modulated energy and a circuit connecting the output electrodes of said rectifier to said second resistive means to impress thereon additional controlling potentials to control the bias of the modulator tube in accordance with the modulations in the output circuit of said carrier frequency tube.

4. In a modulation system a carrier frequency tube having electrodes connected in circuits in which wave energy to be modulated may be set up and having output electrodes, a modulator tube having a control grid and cathodes connected with a source of modulating potentials and having output electrodes, a source of direct current potential, a circuit connecting the output electrodes of both of said tubes and said source of direct current potential in a series modulation circuit, a plurality of resistances in series between the control grid and cathode of said modulator tube, means for impressing a direct current potential on one of said resistances to bias the control grid of said modulator tube relative to the cathode by a fixed amount, and means for applying additional biasing potential to another of said resistances to additionally control the bias on the control grid of said modulator tube by an amount which varies as the modulations on the wave energy vary, comprising a rectifier having input electrodes coupled to electrodes of said carrier frequency tube, said rectifier having output electrodes coupled to said other of said first named resistances.

5. In a modulation system a carrier frequency tube having electrodes in circuits in which wave energy to be modulated is caused to flow and

having output electrodes, a modulator tube having a control grid and cathode connected with a source of modulating potentials and having output electrodes, a source of direct current potential, a circuit connecting the output electrodes of said tubes and said source of direct current potential in a series modulation circuit, the output electrodes of said modulator tube being in the high potential side of said series modulation circuit, a plurality of resistances in series between the control grid and cathode of said modulator tube, means for impressing a direct current potential derived from said source of direct current potential on one of said resistances to bias the control grid of said modulator tube relative to the cathode by a fixed amount, and means for applying additional biasing potential to another of said resistances to additionally control the bias on the control grid of said modulator tube an amount which varies in accordance with the modulations on said wave energy comprising a rectifier having input electrodes coupled to electrodes of said carrier frequency tube, said rectifier having output electrodes coupled to said other of said first named resistances.

6. In a modulation system of the type wherein a discharge tube stage has electrodes connected in a circuit in which wave energy to be modulated is caused to flow and has output electrodes connected in a series modulation circuit with a modulator tube having electrodes on which modulating potentials are impressed, both tubes being connected in series with a source of direct current potential to accomplish modulation of said wave energy by said modulating potentials, said modulator tube being in the high potential end of said series modulation circuit, means for impressing a direct current biasing potential on a controlling electrode of said modulator tube, an impedance for impressing an additional controlling potential on a controlling electrode of said modulator tube which varies in accordance with the modulations on said wave energy, and rectifying means coupling electrodes of said discharge tube to said impedance to impress thereon additional controlling potentials to control the bias of said modulator tube in accordance with the modulations on said wave energy.

ERNEST GREEN.
